UNITED STATES PATENT OFFICE.

JAMES F. PECK, OF SHERMAN, TEXAS.

HOPPER-DOOR.

1,272,515.

Specification of Letters Patent. Patented July 16, 1918.

Application filed March 12, 1917. Serial No. 154,256.

To all whom it may concern:

Be it known that I, JAMES F. PECK, a citizen of the United States, residing at #810 N. Walnut street, Sherman, in the county of 5 Grayson and State of Texas, have invented certain new and useful Improvements in Hopper-Doors, of which the following is a specification.

This invention relates to a hopper door especially designed for use with a vertically movable weighing hopper adapted to receive and weigh cotton seed, the seed being discharged from the hopper through said door into a receiver and from thence conveyed by a screw conveyer to any suitable chute or other storage place.

The invention resides especially in the manner of hinging and operating the door, and in the novel features of construction 20 hereinafter described, pointed out in the claims, and shown in the accompanying drawings, in which:—

Figure 1 is a bottom plan view of a hopper equipped with a door and door operating mechanism in accordance with the present invention, the door being shown in closed position.

Fig. 2 is a vertical section through the lower portion of the hopper the door being 30 in open position.

Fig. 3 is a vertical section, the door being in closed position, and

Figs. 4 and 5 are detail perspective views 35 of certain levers of the door operating mechanism, shown detached.

Referring to a detail description of the drawings wherein like reference characters designate corresponding parts throughout the several views, 1 designates the hopper 40 provided at its lower end with an inwardly inclined wall 6, and arranged opposite said wall 6 is a hinged door 7 normally closing the hopper bottom.

The invention relates particularly to the 45 means for holding this door closed against the weight of seed pressing on it during the filling of the hopper and the means for opening the door when the desired weight of seed has been introduced.

Across the lower front of the hopper is a 50 square shaft 8 mounted in bearings 9, the shaft having of course cylindrical portions fitting the bearings. Extending inwardly from the shaft toward the door are two 55 levers 10 in the form of bars having square sleeves 11 at their outer ends to fit the

shaft 8, flanged as at 12 on one side and perforated as at 13.

On the lower outer face of the door is mounted a second shaft 14 and on said shaft 60 are mounted levers 15 having at their inner ends cylindrical sleeves 16 to turn on the shaft 14 and having at their outer ends a side flange 17 with perforation 18.

A third shaft 19 passes through the perforations 13 and 18 and connects the levers together and to said shaft are connected the lower ends of coil springs 20, the upper ends of the springs being secured to the hopper.

When the door is closed the levers 15 overlap and rest on the levers 10 and the pressure of the seed on the door causes a thrust along the line of the levers and against the inner vertical side of the square shaft 8 and the greater the pressure the more firmly locked 75 said door becomes.

To one end of the shaft 8 is connected an operating lever 21 with a pull chain 22, within easy reach of the scale attendant.

It will be obvious from Figs. 2 and 3 of 80 the drawing that when the shaft 8 is rocked by lever 21 the lever 10 will swing downwardly into perpendicular position, thus drawing downwardly and outwardly the shaft 19 and throwing the lever 10 from a 85 horizontal to an inclined position, causing the door 7 to open.

What I claim is:—

1. The combination with a hopper having a door hinged at its upper end to one side 90 wall of the hopper at a point above the lower end thereof, and adapted to extend at a downward inclination across the bottom of the hopper and engage a portion on the opposite side wall when in closed position, of operating means for the door including a shaft extending across that side of the hopper to which the door is hinged, said shaft being supported for rotation on the hopper below the hinged connection of 100 the door, a lever pivotally connected at one end with the lower end of the door, a second lever pivotally connected at one end to one end of the first mentioned lever and fixedly secured at its other end to said shaft, and a coiled spring connected at one end with 105 said levers at the pivotal connection thereof with each other, and connected at its opposite end with the hopper above said shaft, said levers when the door is in closed position extending in longitudinal alinement 110 with each other.

2. The combination with a hopper having a door hinged at its upper end to a side wall of the hopper at a point above the lower end thereof and adapted to extend in a downward inclination across the bottom of the hopper and to engage a portion on the opposite side wall of the hopper when in closed position, of operating means for the door including a shaft extending across that side 5 of the hopper to which the door is hinged, said shaft being supported for rotation on the hopper below the hinged connection of the door, a lever connection between opposite end portions of the shaft and opposite 10 side portions of the door at the lower end thereof, each lever connection including a lever pivotally connected at one end with the door and a lever fixedly secured at one end to said shaft, a transverse shaft pivotally connecting the inner ends of the pairs 15 of levers, and a coiled spring connected at one end to said last mentioned shaft and at its opposite end to the hopper above the first mentioned shaft, each pair of levers being adapted to extend in longitudinal alinement when the door is in closed position.
3. The combination with a hopper having a door hinged at its upper end to a side wall

of the hopper at a point above the lower end thereof and adapted to extend in a downward inclination across the bottom of the hopper and to engage a portion on the opposite side wall of the hopper when in closed position, of operating means for the door including a shaft extending across that side 30 of the hopper to which the door is hinged, said shaft being supported for rotation on the hopper below the hinged connection of the door, a lever connection between opposite end portions of the shaft and opposite 35 side portions of the door at the lower end thereof, each lever connection including a lever pivotally connected at one end with the door, and a lever fixedly secured at one end to said shaft, a transverse shaft pivotally connecting the inner end of the pairs 40 of levers, and a pair of coiled springs each connected at one end to said last mentioned shaft at one end thereof and connected at its opposite end to the hopper above the first 45 mentioned shaft, each pair of levers extending in longitudinal alinement with each other when the door is in closed position.

In testimony whereof I affix my signature.

JAMES F. PECK.
